UNITED STATES PATENT OFFICE

HUGH B. BARBER, OF TOLEDO, OHIO, ASSIGNOR TO SURFACE COMBUSTION CORPORATION, OF TOLEDO, OHIO, A CORPORATION OF NEW YORK

COMBUSTION OF GASEOUS FUEL

Application filed October 15, 1930. Serial No. 488,820.

This invention relates to a method of and apparatus for mixing air and fuel gas and treating the mixture in a manner to secure a long luminous flame when the mixture is burned in a confined space whereto free air does not have access.

It is a well known fact that a luminous flame constitutes a source of radiant heat. However, the attainment of a long luminous flame from the combustion, in a confined space to which free air does not have access, of fuel gas presents many practical difficulties. The present invention therefore aims to provide a simple and practical method of and apparatus for forming a fluid fuel mixture which upon being burned in a confined space will produce a long luminous flame.

The invention will be best understood by reference to the detailed description taken in connection with the accompanying drawings wherein the preferred form of apparatus is illustrated.

Referring to the drawings,

Fig. 1 is a longitudinal section of the apparatus and so much of a furnace wall as is necessary to explain the invention.

Fig. 2 is a transverse section taken on line 2—2 of Fig. 1 and viewed in direction of the arrows.

Fig. 3 is an enlarged view of a detail of the oil atomizing apparatus and having a portion broken away so as to clearly show the interior passages.

In the drawings, 4 indicates a portion of a furnace wall provided with a refractory throat 6 rounded off at its ends as shown. Secured to the outer side of the wall 4 is a casing or hood comprising a front plate 8, a cylindrical portion 10, and a flange 12 through which latter are passed bolts 14 for securing the hood to the furnace wall. The cylindrical portion 10 is provided with radial apertures 16 for the admission of air, and disposed about said portion is a split band 18 provided at its split with upstanding lugs or flanges 20 through which is passed a bolt 22 for tightening the band to hold it in adjusted position.

The band is in effect a damper or shutter for controlling the effective areas of the ap-

tures 16, it being understood that the band is adjustable axially of the cylindrical portion 10 to expose said apertures. The interior of the casing may be provided with radial partitions or vanes 24 for strengthening or imparting rigidity to the casing as a whole.

Projecting into said hood or casing through an opening in the end wall 8 thereof is a water-cooled head 26 which is fixedly secured to said wall in any suitable manner as by bolts 28 passed through a radial flange 30 on said head 26. Positioned in the head 26 and extending therefrom is a tube 32. Welded to the outside of the tube is a ring 34 which abuts against a shoulder within the head 26 and thus limits inward movement of the tube. At the outer end of the tube 32 is a body 36 forming an entrance cone to the tube, this body being held in place on the tube by rods 38 secured at one of their ends to the head 26 and at their other ends passing through and projecting beyond the radial lugs 40 on said body 36. Stiff coil springs 42 between the flange 40 and the headed terminal ends of said rods serve to compensate for unequal expansion between the rods 38 and tube 32.

Telescoped over and projecting from the cone body 36 is a cylindrical member 44, bolts 46 holding the parts in fixed position. Said member is provided with radial apertures 48 the effective areas of which are controlled by a damper shown as a split band 50 provided at its split by upstanding lugs or flanges 52, through which are passed a bolt 54 for tightening and holding the band in place. This band is preferably provided with apertures 56 adapted to register with the apertures 48 in the member 44. By turning the band the effective areas of the apertures may be readily controlled as will be readily understood.

The front end of the cylindrical member 44 is closed by a plate 58 which is fixedly secured to said member in any suitable manner as by bolts 60. On the inner side of the plate is formed an annular chamber 62 having an inlet connection 64 for fuel gas. 66 indicates jet orifice nozzles removably secured in the side wall 68 of the chamber 62, four such nozzles being shown. Removability of the nozzles is

desirable in order to permit different size nozzles to be provided depending on the character of the fuel gas to be utilized. The parts 44 and 58 constitute in effect a casing forming 5 a hood at the front end of the tube 32.

Positioned within the tube 32 at the discharge end thereof is a spider 70 through the hub of which extends a tubular body 72 having a restricted discharge orifice or nozzle 74.

- 10 Forming an extension of said body is a pipe 76 which projects through a central opening in the closure plate 58 at the other end of the apparatus, there being secured to the outer end of the pipe a chambered fitting 78 15 fixedly secured to said plate in any suitable manner. In communication with the chamber of the fitting is a pipe 80 for supplying a fluid suitable for atomizing fuel oil.

Adjustably mounted in the fitting 78 is a 20 tubular fitting 82 from one end of which extends a fuel oil supply pipe 84 and from the other end of which extends a pipe 86 which terminates within the tubular member 72 at the other end of the apparatus.

- 25 Slidably mounted within the tubular member 72 is a chambered cylindrical member 88 into which the pipe 86 is screwed, this member being exteriorly provided with axially extending slots 90 to permit fluid from the pipe 76 to flow past said member. 92 indicates outlet ports from the chamber within said member 88, it being noted that these ports are obliquely disposed with respect to the axis of said member. Formed as an extension of member 88 is a head 94 provided with spiral grooves 96 in its surface, the head tapering off to a tip as shown. The major diameter of this head may be such as to form a sliding fit in the bore of member 72 but as shown it is 40 preferred that said diameter be somewhat less than said bore.

The body 88 intermediate its ends is of reduced diameter as indicated at 98 to form, as it were, an annular chamber whereinto the 45 fuel oil from the ports or passages 92 is projected to be picked up by the stream of atomizing fluid flowing along the slots 90.

The mode of operation of the apparatus will now be briefly described. Fuel gas under 50 relatively high pressure, say a pressure of 25 lbs. per sq. in., is supplied to the chamber 62 by pipe 64. This gas flows from the chamber 62 through the jet orifice nozzles 66 in the side wall 68 of the chamber and induces 55 a flow of air through the apertures 48 in the cylindrical casing 44, the split band damper 50 being so adjusted that considerably less air than is required for complete combustion of the gas is entrained. The tube 60 32 is a relatively long one and consequently the air and gas become thoroughly mixed by the time the discharge end of the tube is reached.

The gas rich mixture is discharged from the 65 tube 32 into the throat 6 across an intervening

air space and consequently tends to induce a flow of air through the apertures 16 in the surrounding casing, the split band damper 18 being so adjusted that the balance of the air needed for complete combustion of the gas is entrained at this second entraining stage. Complete mixing of the additional air and the gas rich mixture does not, however, occur in the throat 6 since the latter is too short for that purpose, but nevertheless the mixture, such as it is, is combustible although it burns with less speed than an explosive gaseous mixture would burn. The resulting flame is relatively long and appreciably luminous but not sufficiently luminous to form a source of intense radiant heat and it is difficult if not impossible to secure flame temperatures in excess of 2750° F. 70 75 80

In order to make the mixture formed as aforesaid highly luminous, there is introduced into the gas rich mixture leaving the tube 32 a relatively small amount of fuel oil in atomized condition. Fuel oil under suitable pressure is conducted by the pipe 84, fitting 82, and pipe 86 to the chambered body 88 and from thence the oil is discharged through passages 92 into the annular space 98. 85 90 95

The atomizing medium is conveniently fuel gas under pressure from the same source of supply as the gas which is delivered by pipe 64 to the gas chamber 62. This atomizing medium is delivered by pipe 80 into the chambered fitting 78 from whence it flows through pipe 76 into the bore of the member 72. Upon reaching said bore the gas flows along the slots or channels 90 in the cylindrical body 88 and past the oil outlet ports 92 in the member 88 on its way to the outlet orifice 74. It follows therefore that the gaseous medium will become impregnated with oil vapors, it being understood that the body 72 will be relatively hot due to absorption of heat from the furnace. The atomizing medium being so laden with oil vapors must flow along the spiral paths formed on the head 94 to reach the final outlet 74 from the chambered body 72 and hence the mixture of oil vapors and the atomizing medium will leave the outlet orifice 74 with a whirling motion with the result that 100 105 110

the mixture tends to spread out into the path of the gas rich mixture leaving the tube 32. By adjusting the position of the spiraled head 94 with respect to the outlet orifice 74, which adjustment is effected by turning the fitting 82 at the opposite end of the apparatus, the degree of whirling motion of the mixture leaving the nozzle 74 can be appreciably controlled, the closer the head 94 is to the outlet orifice 74 the more pronounced being the 115 120 125 whirling motion of the mixture.

It was previously stated that the split band damper 18 would be so adjusted that just sufficient air for complete combustion of the gas rich mixture leaving the tube 32 would be entrained. However, during such times as 130

said mixture is being impregnated with oil vapors as said, the damper 18 is adjusted to admit enough additional air to compensate for the additional fuel introduced into the 5 mixture. The amount of oil required to increase the luminosity of the flame is relatively small.

From the foregoing it will be seen that the 10 present invention provides an apparatus for efficiently burning fuel gas in a manner to produce a long flame although of not very intense luminosity and provides means for increasing the luminosity by adding in a simple manner a relatively small amount of fuel oil. 15 The invention finds special application in connection with long furnaces where a long flame is desired.

What I claim is:

1. A burner apparatus comprising in combination, a body having an opening therethrough forming a throat for the passage of combustible mixture, a casing secured to said body and forming a hood at the entrance to said throat, a relatively long tube projecting from said casing from a point therewithin, a casing forming a hood at the outer end of said tube, means for discharging fuel gas into said tube from within the confines of the second-mentioned casing, means individual to each of said casings for individually controlling the admission of air thereinto, and means within the confines of the first-mentioned casing for discharging fuel oil into the gaseous mixture issuing from said tube. 35

2. A burner apparatus comprising in combination, a body having an opening therethrough forming a throat for the passage of combustible mixture, a casing secured to said body and forming a hood at the entrance to said throat, a relatively long tube projecting from said casing from a point therewithin, a casing forming a hood at the outer end of said tube, means for discharging fuel gas into said tube from within the confines of the second-mentioned casing, means individual to each of said casings for individually controlling the admission of air thereinto, and means adjacent the discharge end of said 45 tube for discharging atomized fuel oil into the gaseous mixture issuing from the tube. 50

3. A burner apparatus comprising in combination, a body having an opening therethrough forming a throat for the passage of combustible mixture, a casing secured to said body and forming a hood at the entrance to said throat, a relatively long tube projecting from said casing from a point therewithin, a casing forming a hood at the outer end of 55 said tube, means for discharging fuel gas into said tube from within the confines of the second-mentioned casing, means individual to each of said casings for individually controlling the admission of air thereinto, a tubular member within said tube adjacent the 60

discharge end thereof, means for delivering fuel oil to the interior of said member, and means within said member for imparting a whirling motion to the oil as it leaves said member. 70

4. A burner apparatus comprising in combination, a body having an opening therethrough forming a throat for the passage of combustible mixture, a casing secured to said body and forming a hood at the entrance to said throat, a relatively long tube projecting from said casing from a point therewithin, a casing forming a hood at the outer end of said tube, a gas chamber within the last-mentioned casing, jet-orifice nozzles positioned in a side wall of said chamber and set to discharge into said tube, means individual to each of said casings for individually controlling the admission of air thereinto, and means at the discharge end of said tube for spraying fuel oil into the gaseous mixture issuing from said tube. 80 85

In testimony whereof I affix my signature.

HUGH B. BARBER.
